UNITED STATES PATENT OFFICE.

FRANKLIN C. HOCKENSMITH, OF PITTSBURG, PENNSYLVANIA.

SELF-OILING WHEEL.

No. 851,354.

Specification of Letters Patent.

Patented April 23, 1907.

Application filed July 3, 1906. Serial No. 324,651.

To all whom it may concern:

Be it known that I, FRANKLIN C. HOCKENSMITH, a citizen of the United States, residing at Pittsburg, in the county of Allegheny and State of Pennsylvania, have invented new and useful Improvements in Self-Oiling Wheels, of which the following is a specification.

This invention relates to a valve or closure for the inlet of an oil chamber, and particularly the chamber of a self-oiling wheel.

The primary object is to provide improved means for holding the inwardly opening valve normally seated.

15 A further object is to so construct the valve and valve seat that the valve may be readily opened by the spout of the oiler, and when open afford a free and unobstructed passage into the chamber.

20 These and other objects of the invention are fully described in the accompanying specification.

The invention is designed primarily for a self-oiling mine car wheel, and is so illustrated in the accompanying drawing, Figure 1 being a vertical sectional view through the hub of the mine car wheel, taken on line 1-1 of Fig. 2. Fig. 2 is a sectional view, taken at right angles to Fig. 1, on line 2-2 thereof. 25 Fig. 3 is a view on a larger scale of a portion of the oil chamber, showing the position of the valve when open for the admission of oil. Figs. 4 and 5 are detail views.

30 Referring to the drawing, 2 designates the hub of a wheel, here shown formed with an annular oil chamber 3, surrounding eye 4.

35 5 are the spokes radiating from the hub and carrying the rim and tread, not shown. Wheels having chambered hubs of various 40 construction are now in use, and the invention is not restricted to a wheel of any particular design.

In applying my improvement, I cast in outer wall 6 of the oil chamber an internally 45 threaded bushing 7, which receives the open externally threaded valve seat 8 through which the oil is introduced. The outer face of this seat member is beveled or coned at 9, and also formed with an external wrench 50 hold 10, while the inner face thereof is beveled or coned at 11, the inner and outer surfaces being separated by a comparatively thin or narrow annular ridge 12.

55 Supported within the oil chamber in line with the valve seat, and spaced inwardly therefrom, is the open-end holder 13, here

shown in form of a tube, and sustained by having its end cast in the inner wall 6' of the oil chamber. The holder may be provided with lateral openings 13' to prevent the accumulation of dirt, sediment, etc.

Fitting loosely within the holder is coiled spring 14, which is under constant tension and operates to hold the valve normally seated and closed. The valve consists of a stem 65 portion 15 which extends into the coiled spring, and the head 16 against the rear or inner face of which the spring bears. This rear face is preferably beveled as shown at 16' to render less likely the accumulation of 70 obstructing foreign matter between the spring and head. The outer face of the head is flat, and its edge is slightly beveled at 16" to make a tight fit in beveled face 11 of the valve seat. The open-end of the tubular 75 holder is flared slightly or beveled at 13" so that when the spring is deflected laterally when the valve opens it will not catch on the end of the holder. The inner end of the valve stem 15 is tapered at 15' so that when 80 forcing the valve inward said extremity will slip past and not catch on the convolutions of the spring.

Figure 3 illustrates the position of the valve when opened by pressure of the oiler-spout 17. With the latter introduced at an angle, as shown, it is impossible for its open end to be closed or obstructed by the flat outer face of the valve. Furthermore, this flat face facilitates the sliding or slipping 90 movement of the spout-end sidewise or toward the periphery of the valve-head, thus discharging the oil directly into the oil chamber. The formation of the inner and outer faces of the seat member 8 is such as to facilitate such angular positioning of the oiler-spout, there being only the narrow ridge 12 to limit such movement.

In consequence of the comparatively small area of the engaging surfaces between 100 the valve and its seat, the valve forms an effective seal. With a larger engaging surface, foreign matter deposited on any portion thereof would hold the valve unseated, whereas, with my improved valve, the relatively thin or narrow edge of the head tends to cut away or displace any obstruction that may exist. It will be noted that the base or inner end of holder 13 is somewhat within the line of the inner face of chamber-wall 6', and that when the valve is closed the valve-engaging end of the spring projects somewhat

into the plane of chamber wall 6. A space of maximum length is thus afforded for the coiled spring, thus permitting of the use of a spring of such length that when contracted, as it is when the valve is opened by the insertion of the oiler, the tension thereof is not materially increased.

I know of the patent to Robinson, No. 552,681, May 19, 1891, and am therefore aware that I am not the first to propose a normally closed, inwardly opening, spring actuated valve having valve holding means spaced inward and away from the oil inlet or valve seat. I believe, however, that I am the first to provide a construction of this type wherein the spring is positively held within a holder, also a construction wherein no oil-tight fit is necessary between the valve and its holding means. Also, by holding the valve in the manner shown and described it has lateral play when away from its seat which facilitates its opening movement, and also enables it to center properly in its seat when closing, advantages not possessed by a positively guided valve.

I claim:

1. The combination of an oil chamber having a filling opening in one wall thereof, the wall opposite the filling opening being closed, a holder secured to said opposite closed wall and projecting toward the filling opening, the secured end of the holder being closed and its opposite end open, a coiled spring within the holder and projecting therefrom toward the filling opening, and a headed valve having its stem projecting part way through the spring and holder, the valve stem being smaller than and loosely fitting the interior of the spring with the latter bearing against the back of the valve head and holding the latter normally seated and closing the filling opening.
2. The combination of a wheel, an oil chamber communicating with the interior of

the wheel hub, the chamber having a filling opening in one side wall thereof with the wall opposite the filling opening closed, a tubular holder within the chamber and extending toward the filling opening, the end of the holder facing the filling opening being open, a coiled spring seated in the holder and extending through the open end thereof toward the filling opening, a headed valve having its stem smaller than and loosely fitting within the spring, the spring bearing against the back of the valve head and holding it normally seated and closing the filling opening.

3. The combination of an oil chamber having a filling opening, a coiled spring in line with and expansible toward the filling opening, spring holding means, a headed valve normally closing the filling opening by the action of the spring, the valve stem extending part-way through the coiled spring and having its inner end coned in order to freely pass the inner surface of the spring when the valve is pushed inward.

4. The combination of an oil chamber having a filling opening, the outer portion of the opening being coned inwardly and the inner portion coned outwardly, a tubular open-end holder within the chamber and extending toward the filling opening, a coiled spring seated in the holder and normally projecting therefrom, and a valve having a flat head closing against the inner coned face of the opening and a shank projecting loosely into the spring from the head and partially through the holder, the valve being capable of limited lateral movement when unseated.

In testimony whereof I have signed my name to this specification in the presence of two subscribing witnesses.

FRANKLIN C. HOCKENSMITH.
